UNITED STATES PATENT OFFICE.

EDGAR T. MEADOR, OF GILES, TEXAS.

CATTLE-GUARD.

SPECIFICATION forming part of Letters Patent No. 699,925, dated May 13, 1902.

Application filed February 18, 1902. Serial No. 94,678. (No model.)

To all whom it may concern:

Be it known that I, EDGAR T. MEADOR, a citizen of the United States, residing at Giles, in the county of Donley and State of Texas, 5 have invented a new and useful Cattle-Guard, of which the following is a specification.

The invention relates to improvements in cattle-guards.

The object of the present invention is to 10 improve the construction of cattle-guards and to provide an exceedingly simple and inexpensive one of great strength and durability capable of effectually preventing stock from passing over it and adapted to expose fully 15 the track on which it is mounted, so that any defect may be readily detected and repaired.

A further object of the invention is to provide a cattle-guard of this character in which the wires may be readily replaced should they 20 become broken and in which one wire may be renewed or repaired without affecting the other wires.

The invention consists in the construction and novel combination and arrangement of 25 parts hereinafter fully described, illustrated in the accompanying drawings, and pointed out in the claim hereto appended.

In the drawings, Figure 1 is a perspective view of a cattle-guard constructed in accordance with this invention. Fig. 2 is a plan view of a portion of the cattle-guard. Fig. 3 is a detail view of one of the braces.

Like numerals of reference designate corresponding parts in all the figures of the drawings.

1 and 2 designate central and side sections of the cattle-guard mounted upon the cross-ties 3 and arranged between and at opposite sides of the rails, as clearly illustrated in Fig. 40 1 of the drawings. Each of the sections consists of an oblong frame and longitudinal wires 5, which are preferably composed of two or more strands and which are provided at intervals with barbs. The frame of the 45 central section of the cattle-guard is composed of side and end bars 7 and 9, of angle-iron, having vertical and horizontal flanges or wings, the horizontal flanges being secured to the cross-ties in any suitable manner. The 50 side sections, which are located outside the rails, have their frames composed of side and end bars 8 and 9, of angle-iron, and the end

bars of all of the sections are perforated for the reception of adjusting devices 10, consisting, preferably, of eyebolts and adapted 55 for straining the barbed wire to the desired tension. These adjusting devices by being arranged independently of one another will permit any one of the wires to be readily repaired or renewed should it become broken 60 without removing or otherwise affecting the other wires. The frames are supported by transverse braces 11 and 12, preferably arranged at the center, as shown in Fig. 1, and consisting of heavy sheet metal or angle-iron 65 and composed of sides or flanges arranged at an acute angle to each other and provided with notches 13 for the reception of the barbed wires, which are secured to the braces by short ties 14. The short ties, which are constructed of wire, extend beneath and partially 70 around the braces and have their terminals secured to the longitudinal wires 5. The ends 15 of the braces are straight or flat and are perforated for the reception of suitable fastening devices for securing them to the horizontal flanges of the frames of the sections of the cattle-guard. The spaces between the cross-ties form pits beneath the sections of the cattle-guard, and it will be impossible 75 for an animal to cross over the cattle-guard without cutting its legs on the barbed wires, and the latter will effectually prevent stock from passing over it. The cattle-guard sections are open, and they expose the track, so 80 that any defect therein may be readily detected and repaired, and it will not cause the accumulation of water, and thereby injure the road-bed.

Arranged at opposite sides of the cattle-guard sections are wings or fence-sections 16, forming guards and consisting of upright frames tapered at their inner ends toward the track and provided with horizontal barbed wires 17 and having spikes 18 and 19 extending along the top and inner ends of the sections. The frames 16 are composed of top and bottom bars 20 and 21, a vertical outer end bar 22, and an inclined inner end bar 23, and these bars are constructed of angle-iron 95 100 and have their flanges suitably connected at their ends. The frames are supported by vertical braces 24, approximately V-shaped in cross-section, having sides or flanges ar-

ranged at an acute angle and provided with flattened ends which are riveted or otherwise secured to the top and bottom bars. The barbed wires are secured at their ends to the 5 inner and outer end bars by adjusting devices 25, consisting, preferably, of eyebolts, and the said wires are secured to the vertical braces 24 by ties 26, extending partially around the said braces and secured at opposite 10 sides thereof to the horizontal wires 17. The braces are provided at intervals with notches for the reception of horizontal barbed wires, and the latter are held in the notches by the wire-ties 26. The frames are provided at their ends with depending vertically-disposed angle-plates 27, which are bolted or otherwise secured to short posts or stakes 28; but the wings may be mounted in any other suitable manner.

20 It will be seen that the cattle-guard is exceedingly simple and inexpensive in construction, that it is adapted to be readily applied to a track, and that it will thoroughly expose the same, so that any defects may be

readily detected and repaired. Furthermore, 25 it will be clear that the cattle-guard is capable of effectually preventing stock from crossing it, that the spaces between the cross-ties form pits, and that should any one of the barbed wires become broken it may be readily repaired without affecting the other wires.

What I claim is—

A cattle-guard comprising the central and side sections, and the side wings consisting of upright frames of angle-iron tapered toward the said sections and provided at the top and inner end with spurs or projections, barbed wires, and braces supporting the barbed wires and the frames, substantially as described.

In testimony that I claim the foregoing as my own I have hereto affixed my signature in the presence of two witnesses.

EDGAR T. MEADOR.
